UNITED STATES PATENT OFFICE.

LOUIS C. NICHOLS, OF MILWAUKEE, WISCONSIN, ASSIGNEE, BY MESNE ASSIGNMENTS, TO ALLIS-CHALMERS MANUFACTURING COMPANY, A CORPORATION OF DELAWARE.

CONNECTOR.

1,092,589.

Specification of Letters Patent.

Patented Apr. 7, 1914.

Application filed November 20, 1909. Serial No. 528,063.

To all whom it may concern:

Be it known that I, LOUIS C. NICHOLS, a citizen of the United States, residing at Milwaukee, in the county of Milwaukee and State of Wisconsin, have invented certain new and useful Improvements in Connectors, of which the following is a full, clear, and exact specification.

This invention relates to improvements in connectors or couplers for electric conductors or cables, and has for one of its objects the provision of a connector consisting of parts which are inexpensive to manufacture and which can be quickly united and so effectively clamped together that the resistance of the connector is practically negligible.

A further object is the provision of a connector having a construction such that there is no danger of accidental separation between the terminals of the connector or between the terminals and the ends of the conductors or cables connected thereto.

My invention may be briefly summarized as consisting in certain novel details of construction and combinations and arrangements of parts which will be described in the specification and set forth in the appended claims.

In the accompanying drawings, wherein I have shown several modifications of my invention, Figure 1 is a side elevation of a connector constructed in accordance with one form of my invention, the clamping nut not being shown in section. Fig. 2 is a partial section and partial elevation of the same, the section being taken substantially along the line 2-2 of Fig. 1, looking in the direction indicated by the arrows, the ends of the cable or conductor being attached to the terminals of the connector. Fig. 3 is an elevation of a modified form of connector, the terminal members being out of engagement. Fig. 4 is an elevation of a further modification, the ends of the cable being attached to the terminals of the connector.

Referring now to the figures of the drawing, and first to Figs. 1 and 2 it will be seen that the connector includes two terminal members 10 and 11 which are preferably tubular in form and are provided with openings 12 which extend longitudinally through the same and receive conductors 13 which are shown in Fig. 2. The terminal

members are provided with overlapping or 55 interfitting longitudinal extensions 14 and 15, the end of the extension of each terminal member engaging the shoulder 16 formed at the base of the extension of the other terminal member. The opposing longitudinal 60 faces of the overlapping extensions are not relied on, at least not entirely, for the contact surfaces between which current passes from one terminal to the other, but the major portion of the current passes through 65 the abutting end portions of the terminals, so that the engaging faces of the shoulders and ends of the extensions form the main contact surfaces. In order that excellent contact may be obtained between these portions, the terminals are so formed that when the overlapping extensions are drawn together by means to be referred to later, pressure or a jamming action will be created between the abutting end faces. For this purpose the engaging faces of the shoulders and the ends of the extensions are slightly beveled, and the parts are preferably so formed 70 that the beveled faces engage one another just before the terminal members are 75 brought in exact alinement, so that when the members are brought in alinement by the clamping member, considerable pressure will be created between the abutting end faces. In order that there will be no endwise movement between the terminal members while they are being clamped together as described and after being united, and to further increase the contact surfaces between the members, the latter are also provided 80 with interlocking transverse projections or lugs. In the construction shown in Figs. 1 and 2, the extension 14 of the terminal member 10 is provided with a transversely extending projection or lug 17 and the extension 15 of the terminal member 11 is provided with a transverse slot 18 so arranged and formed as to receive with a tight fit the projection 17. Preferably a portion of the extension 15 of terminal member 11 is cut 85 away forming a recess 19 and a pair of transverse projections 20 and 21 similar to the projection 17.

The terminal members are held or clamped together by a clamping member, 105 in this case a nut 22 which engages threaded portions 23 and 24 provided on the two terminal members. To clamp the members

together the extensions of the two terminal members are placed one upon the other so that they overlap and so that the transverse projections 17 and 20 interlock. As stated before, the beveled faces of the shoulders and extensions engage one another before the two terminal members are brought into alignment, and as the nut is screwed over the overlapping extensions, a jamming action takes place between the engaging beveled faces, with the result that excellent electric contact is obtained, and the resistance of the connector is practically the same as that of a continuous member formed of a single piece. It will be seen that this jamming action takes place for the reason that the interlocking transverse projections 17 and 20 prevent an endwise or longitudinal shifting of the terminal members when the nut is screwed to clamping position. In order that the nut may be caused to pass from the annular threaded shank of one terminal member, and to engage the threaded extension of the other member, although the two members are not in direct alignment, the first thread on the free end of the extension toward which the nut is screwed is preferably slightly beveled, with the result that the nut may be readily screwed onto the overlapping portions and the jamming action produced by the nut will force the members together with the beveled faces in firm engagement.

The conductors 13 are preferably soldered and sweated into the openings of the terminal members, but as a further means of preventing accidental separation between the conductors and the terminal members, the free ends of the conductors are brought into the recess 19 between the projections 20 and 21 of the extension 15 and are bent laterally or at right angles thus providing at the ends of the conductors hook-like portions 25 which aid materially in preventing the conductors being separated from the terminal members. In order that the conductors may be brought into the recess 19 and then bent laterally, the interlocking projections 17, 20 and 21 are provided centrally thereof with openings or recesses through which the conductors pass as shown clearly in Fig. 2.

In Fig. 3, wherein I have shown a modification of my invention, the terminal members are counterpart or are exact duplicates and are interchangeable. In this figure the terminal members, which are shown at 26 and 27, are provided with overlapping longitudinal extensions 28, the ends of the extensions and the shoulders at the bases of the extensions being preferably beveled, as in the first instance, and being adapted to be forced into intimate contact by the clamping nut 29 which engages suitably threaded portions of the two terminal members. In this case each terminal member is provided

at its free end with a transverse lug or projection 30 and a short distance from the shoulder at the base of the extension with a transverse lug or projection 31, the latter forming with the shoulder a transverse slot 32 which receives the projection 30 of the other member. Between the projections 30 and 31 of the two terminal members is a recess 33 in which the ends of the conductors may be received and bent as shown in Fig. 2. In this construction, as in the first construction, when one terminal member is placed on the other so that the extensions overlap and the transversely extending projections interlock, and when the nut is screwed over the overlapping extensions, the beveled faces are forced firmly in engagement with one another, the interlocking transverse lugs or projections preventing relative endwise or longitudinal movement of the terminal members.

In the modification shown in Fig. 4 the terminal members 34 and 35 are provided, as in the first instances, with overlapping extensions 36 and 37, the ends of the extensions and the ends of the shoulders being beveled and being clamped together by a nut 38. In this case the terminal member 34 is similar to the terminal member 10 of Fig. 1, being provided at its free end with a transverse projection or lug 39. The extension of terminal member 35 is provided with a slot 40 which receives the projection 39 with a tight fit, but in this modification the extension 37 is not provided with a recess corresponding to the recess 19 of Figs. 1 and 2. The ends of the conductors, which are shown at 41 do not, in this case, extend beyond the shoulders at the bases of the extensions and will be soldered and sweated in the sockets of the terminal members as first described. The construction of the connectors shown in this modification is otherwise the same as the construction of the connector shown in Figs. 1 and 2 and need not be further described.

It will be seen that I have provided connectors which answer all the requirements very effectively, but are susceptible of considerable modification in the details of construction. I aim, therefore, to cover in my claims all modifications which do not involve a departure from the spirit and scope of my invention.

What I claim as new and desire to secure by Letters Patent is:

1. In a cable connector, a pair of terminal members having overlapping longitudinal extensions comprising body portions adapted to engage each other and provided with beveled ends, correspondingly beveled shoulders being formed on the members at the bases of the extensions, the line of engagement between the body portions being at an angle to the beveled ends, and means serving

to draw the beveled faces of the ends and shoulders into intimate contact and for clamping the members together.

2. In a cable connector, a pair of terminal members having interfitting longitudinal extensions provided with beveled ends and having beveled shoulders at the bases of the extensions, one of the extensions having at its free end a transverse projection and the other having a transverse slot which receives the projection, and means engaging the longitudinal extensions and serving to force said beveled surfaces into engagement and to clamp the terminal members together.
3. In a cable connection, a pair of terminal members having overlapping extensions and having openings extending through the same, said extensions having between the adjacent faces thereof a recess, cable terminals extending through the openings in the terminal members and having their free ends projecting into said recess and bent laterally therein.
4. In a cable connector, a pair of terminal members having overlapping longitudinal extensions provided with body portions adapted to engage each other and beveled ends, beveled shoulders at the bases of said extensions, and securing means serving to force said beveled ends into engagement with

said beveled shoulders and to clamp the terminal members together, the line of engagement between said body portions being at an angle to the beveled faces of said ends and shoulders.

35

5. In a cable connector, a pair of terminal members having overlapping longitudinal extensions provided with beveled ends and having beveled shoulders at the bases of the extensions, and threaded securing means adapted to embrace said extensions and serving to move said extensions transversely relatively to each other into engagement and to clamp the terminal members together.

6. A cable connector, comprising a pair of terminal members having extensions adapted to overlap when the members are in assembled condition, each member having an opening therethrough adapted to receive a conductor, and said extensions being provided with cut away portions adapted to align and form a recess when the members are in assembled condition.

Milwaukee, Wis., Nov. 5, 1909.
In testimony whereof I affix my signature, in the presence of two witnesses.

LOUIS C. NICHOLS.
